UNITED STATES PATENT OFFICE.

VICTOR H. KLINE, OF LAKEWOOD, OHIO, ASSIGNOR TO THE AMERICAN MULTIGRAPH COMPANY, OF CLEVELAND, OHIO, A CORPORATION OF OHIO.

PRINTING DEVICE HAVING CHANGEABLE FORM.

Application filed April 7, 1926. Serial No. 100,246.

This invention relates to a printing device employing a changeable form and an inking ribbon overlying the form, and more particularly such a device where the form is on a rotary drum and coacts with a roller platen.

The object of the invention is to provide simple means for enabling the ready installation of the removable form beneath the inking ribbon without causing such ribbon to smudge the platen or otherwise interfering with the printing action.

My invention is well adapted for embodiment in a machine of the type of the multigraph, wherein the drum has means for carrying a body form and the ribbon is mounted on spools within the drum and intermediately extends across such form. In such case, I provide a channel adjacent the body form which leads to the end of the drum and which furnishes a passageway for the reception of the removable portion of the form and is provided with overhanging edges for holding it in place.

To enable the removable form to be readily installed beneath the ribbon lying tautly about the drum, I provide a bridge in the form of a thin metal strip extending across the channel just within the region covered by the ribbon. The removable portion of the form is inserted into place beneath this bridge with its printing portion beyond the same. The bridge is located beyond the end of the platen so that it does not interfere with the proper printing action.

My invention comprises the embodiment above described, where the arcuate bridge prevents the ribbon, held taut on a drum, from forming a chord restricting the entrance to the channel, as well as the broader conception of a bridge across any channel which is adapted to receive a changeable form and is covered by an inking ribbon. My invention is hereinafter more fully explained and its essential novel characteristics are summarized in the claims.

In the drawings, which show an embodiment of my invention, Fig. 1 is a vertical section along the axis of a rotary printing machine similar to a multigraph and embodying my invention; Fig. 2 is a plan of a portion of such machine; Fig. 3 is a perspective of a portion of the removable form and the drum with the ribbon supporting bridge beneath which such form portion is in-

serted; Fig. 4 is a detail in vertical section illustrating particularly the channel for the removable portion of the form and the bridge in edge view; Fig. 5 is a vertical section through the machine; Fig. 6 is a diagrammatic enlargement of a portion of Fig. 5 adjacent the channel.

As shown in the drawings, the printing machine proper comprises a rotary drum 10 mounted on a shaft 11 journalled in end frame plates 12 and 13 above a roller platen 14 mounted on a shaft 15. Gearing 16 and 17 and an Oldham coupling 18 connect the drum and platen. Any suitable means, as for example a crank 19, is provided for rotating the drum and platen.

I have shown means mounted on the drum for printing the body of a form letter, such means comprising a flexible metal blanket 20 stretched about a segment 21 on the drum and having raised overhanging projections 22 carrying embossed printing strips 23. The segment is shown as a semi-cylinder resting on the disk-like end members 28 and 29 of the drum and held in place by suitable means as hook-like members 24 engaging the shaft 11. An inking ribbon 25 is shown as mounted on spools 27 carried between the end members of the drum, such ribbon extending intermediately about the type form.

It will be seen that in the construction described, when the drum is rotated, as by means of the crank, paper fed between the drum and platen may be printed by the type characters through the ribbon. The paper may be fed by hand or in some automatic manner if desired.

The removable portion of the form as illustrated in the drawing comprises an address plate A. This plate is shown as provided with overhanging projections a^1 and depressed edge portions a^2 undercurled on themselves for strength. The projections may carry embossed printing strips a .

The drum segment 21 is provided with a longitudinal channel 30 leading from one end of the drum for the reception of the removable portion of the form. I have shown a supporting portion 32 in this channel for the intermediate portion of the plate dividing the channel and leaving two side recesses for the edge flanges, these recesses being beneath overhanging strips 34 on the drum, which retain the removable form in place when it is shoved therein lengthwise.

1. To enable the plate to pass readily under the ribbon, I employ a bridge 40 extending across the channel. This bridge is preferably a flat piece of spring metal intermediate 55ately curved concentrically of the drum and having depressed end portions which are suitably secured to the segment, as by means of a screw 41. The bridge is located just within the region of the inking ribbon 25 so that it supports the extreme edge portion of the ribbon without interfering with its printing action.

10 It will be noticed that the bridge is beyond the region of the platen, so that although 15 it slightly bulges the ribbon at this point, it does not interfere with the printing action or cause any smudging of the platen. The printing portion of the inserted plate is inwardly beyond the bridge. 20 The plate may extend outwardly to the outer side of the bridge, and the segment may be recessed beneath it as at 45, whereby the plate may be readily grasped by the fingers and withdrawn. It may be held in place by friction or otherwise during the 25 operation of the machine.

30 A portion of the end member 12 may be removed as at 46 Fig. 1 to enable access to the channel 30. By stopping the drum with the channel in register with such recess in the frame plate, the installed plate may be readily removed and a substitute inserted beneath the ribbon as illustrated by the broken lines A in Fig. 1.

35 An inspection of Figs. 5 and 6 illustrates the difficulty in inserting the plate particularly beneath a ribbon stretched about a drum, due to the fact that the taut ribbon tends to form a chord across the channel 40 while the printing surface of the inserted plate is arcuate. By providing a correspondingly arcuate bridge sufficiently high to clear the inserted member, as illustrated particularly in Fig. 3, I overcome the difficulty 45 and enable the ready insertion of the plate. Fig. 6 shows at 25 the position of the ribbon across the channel way beyond the bridge, while the broken lines A show how the end of the address plate would abut the ribbon if the bridge were not employed. The bridge may be located in the vertical 50 plane which is just beyond the end of the platen, as the ribbon raised by the bridge will readily be pressed against the adjacent type in operation.

Having thus described my invention, I claim:—

1. The combination of a printing bed 60 having a channel, a removable printing member adapted to occupy the channel, an inking ribbon extending across the channel, and a bridge substantially parallel with the edge of the ribbon and adjacent the entrance of the channel and extending across it beneath the ribbon.

2. The combination of a curved printing bed having a channel, a removable printing member adapted to occupy the channel and having a curved exterior, an inking ribbon extending tautly in an arcuate direction 70 across the channel, and an arcuate bridge adjacent the entrance of the channel and extending across it beneath the ribbon adjacent the edge thereof.

3. In a printing machine, the combination of means for carrying a body form, a channel extending crosswise of the form, a removable form insertable into place along said channel, an inking ribbon extending over the body form and channel, and a bridge extending across the channel beneath the ribbon parallel with and adjacent its edge.

4. The combination of a printing bed having a channel, a removable plate adapted for insertion in the channel, a bridge across the channel, a ribbon overlying the channel and bridge, and a platen adapted to coact with the ribbon and form and terminating short 85 of the bridge.

5. The combination of a curved member adapted to turn on an axis and having a channel parallel with said axis leading to one edge of the member, a bridge across the channel adjacent to such edge, a changeable form portion adapted for insertion beneath the bridge, a ribbon extending taut about the bed and overlying the channel and bridge, and a platen adapted to coact with the ribbon and form but not with the bridge.

6. The combination of a rotary drum, a longitudinal channel therein for a removable printing member, a ribbon overlying the channel and a bridge adjacent the entrance to the channel extending across it beneath the ribbon substantially parallel with the edge of the ribbon.

7. The combination of a rotary drum having a longitudinal channel, a printing plate adapted to be inserted in said channel by endwise movement, a thin bridge extending across the channel adjacent to its entrance, and a ribbon extending over the channel and bridge, the printing plate being retained in position with a portion of the plate extending beyond the edge of the ribbon.

8. The combination of a printing drum, having a longitudinal channel leading to the end of the drum, a changeable form adapted to be inserted in said channel, a bridge extending across said channel, a pair of ribbon spools mounted within the drum, a ribbon having its ends wound up on said spools and extending intermediately across the channel and bridge.

9. The combination of a rotary printing drum, means thereon for carrying a form for printing a body of a letter and having a longitudinal channel leading to the end of the drum, a changeable form adapted to be

inserted in said channel, a bridge extending across said channel adjacent the end of the drum, a pair of ribbon spools mounted within the drum, a ribbon having its ends wound up on said spools and extending intermediate across the form, channel and bridge.

10. The combination of a printing bed having a channel leading to one edge thereof, overhanging ledges at the sides of the channel, a changeable form adapted to be shoved into place with its edges beneath said ledges, a bridge substantially parallel with the edge of the ribbon and extending across the channel adjacent its entrance, an inking ribbon extending over the channel and bridge, and a platen adapted to coact with the ribbon and form.

11. The combination with a rotary drum carrying a form for printing the body of a letter and having a longitudinal channel leading to the end of the drum, overhanging ledges at the sides of said channel for holding therein a changeable portion of the form which may be shoved into place lengthwise,

a bridge extending across the channel, an inking ribbon carried by the drum lying over the channel and bridge, and a roller platen adapted to coact through the ribbon with the body form and changeable portion but not with the bridge.

12. The combination of a rotary printing drum having a channel leading to one edge thereof, overhanging ledges at the sides of the channel, a changeable form adapted to be shoved into place with its edges beneath said ledges, a bridge across the channel adjacent its entrance, a pair of ribbon spools mounted in the drum and carrying the wound up ends of an inking ribbon extending over the channel and bridge, the changeable form when in place having a portion extending beneath and outside of the bridge, a roller platen adapted to coact with the ribbon and form, but not with the bridge, and means for rotating the drum and platen.

In testimony whereof, I hereunto affix my signature.

VICTOR H. KLINE.
